(57) **CLAIM**

The ornamental design for a communication device with a cable connection, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of my design for a communication device with a cable connection.

FIG. 2 is a top view thereof.

FIG. 3 is a left side elevational view thereof.

FIG. 4 is a rear elevational view thereof; the front side is a mirror image.

FIG. 5 is a bottom view thereof; and,

FIG. 6 is a right side elevational view thereof.

The broken line showing of FIG. 1 is for illustrative purposes only and forms no part of the claimed design.
